DESIGN FOR A COMBINED STERILIZING CABINET AND TOILET SEAT

Walter L. Eckhardt, Overbrook, Pa., assignor to Hygeian Corporation, Philadelphia, Pa., a corporation of Pennsylvania

Application April 6, 1940, Serial No. 91,525

Term of patent 3½ years

To all whom it may concern:

Be it known that I, Walter L. Eckhardt, citizen of the United States, residing at Overbrook, county of Philadelphia, State of Pennsylvania, have invented a new, original, and ornamental Design for a Combined Sterilizing Cabinet and Toilet Seat, of which the following is a specification, reference being had to the accompanying drawing, forming part thereof.

Fig. 1 is a front elevational view of a combined sterilizing cabinet and toilet seat showing my new design.

Fig. 2 represents a top plan thereof.

Fig. 3 represents a section on line 3—3 of Fig. 1.

I claim:

The ornamental design for a combined sterilizing cabinet and toilet seat, as shown.

WALTER L. ECKHARDT.
